UNITED STATES PATENT OFFICE.

THEOPHILUS WILLIAMS, OF CHICAGO, ILLINOIS.

DESIGN FOR A RULER.

SPECIFICATION forming part of Design No. 31,390, dated August 15, 1899.

Application filed June 10, 1899. Serial No. 720,097. Term of patent 3½ years.

To all whom it may concern:

Be it known that I, THEOPHILUS WILLIAMS, a citizen of the United States, residing at Chicago, in the county of Cook, State of Illinois, have invented a new and useful Design for a Ruler, of which the following is a specification, reference being had to the accompanying drawings, forming a part thereof.

Figure 1 is a plan view showing my new design. Fig. 2 is a transverse sectional view taken on line 2 2 of Fig. 1.

The leading or material feature of my design consists in an embossed scene representing a naval battle, in which are shown on the right-hand end two American battle-ships in action. On the left-hand end two Spanish battle-ships are shown, one of which is wrecked and sinking. In the distant background mountains and trees and birds flying

are shown. In the center of the scene the sun is seen rising. Shells are exploding in the air. On the right-hand end of the scene an anchor is shown. On the left a large conical shell is shown. A scale *b*, divided by inches and fractions thereof, is formed along the bottom edge. A large bead *a* is formed along the top edge. (Shown in section at Fig. 2.) The marine scene is embossed in high relief.

Having described my invention, what I claim as new, and desire to secure by Letters Patent, is—

The design for a ruler, as herein shown and described.

THEOPHILUS WILLIAMS.
